UNITED STATES PATENT OFFICE.

WALTER D. WOOD, OF CRANSTON, RHODE ISLAND.

PEARL-COAT-DISTRIBUTING MACHINE.

1,424,544.

Specification of Letters Patent. Patented Aug. 1, 1922.

Application filed November 26, 1919. Serial No. 340,846.

To all whom it may concern:

Be it known that I, WALTER D. WOOD, a citizen of the United States, and resident of Edgewood, city of Cranston, in the county of Providence and State of Rhode Island, have 5 invented certain new and useful Improvements in Pearl-Coat-Distributing Machines, of which the following is a specification.

This invention relates to a machine for 10 and method of distributing a coating substance over the surface of a body, to form artificial pearls; and the object of this invention is to provide means for mounting a bead or body of an artificial pearl on a stem 15 or holder and rotate the holder, whereby the pearl revolves about the axis of the holder.

A further object of the invention is to mount the stem or holder in substantially a horizontal plane and rotate the same with 20 the bead thereon for the purpose of causing the solution which forms the coating to flow in a circular direction over the surface of the bead or body during the process of drying.

25 With these and other objects in view, the invention consists of certain novel features of construction, as will be more fully described, and particularly pointed out in the appended claims.

30 In the accompanying drawings:

Figure 1— is a side elevation of my improved machine which is adapted to rotate and also move the work bodily while drying.

Figure 2— is a plan view of the machine, 35 showing a plurality of carrier blocks mounted in spaced apart relation in a machine, each receiving a combined rotating and traverse motion.

Figure 3— is an end elevation on line 3—3 40 of Figure 1.

Figure 4— is a sectional side elevation on line 4—4 of Figure 2, showing the endless driving belt for imparting a traverse motion to the work.

45 Figure 5— is a detailed side elevation sectioned on line 5—5 of Figure 1, of one of the heads illustrating a carrier block mounted thereon; and showing the construction whereby the carrier may be automatically 50 discharged from engagement therewith at a predetermined point in its travel.

Figure 6— is a view of the same head as 55 illustrated in Figure 5, but taken at a right angle thereto to further illustrate the mechanism for discharging the carrier block from the head.

Figure 7— is a detail of the carrier block, showing the work mounted thereon.

Figure 8— is an enlarged view of one of the beads or bodies, showing the hole therein 60 through which it is strung.

Figure 9— is an end view of the head member, showing the squared end which receives the carrier block.

The feature of this invention is the provision of improved means in the manufacture of artificial pearls, to facilitate the method of handling the beads or bodies during the period of drying the coating solution after the solution has been applied 65 thereto. In practice it is found that if the work after having been dipped in a coating solution, is set upright the solution while drying will run from the upper side of the pearl down to the lower side thereof forming 70 an uneven coating or a coating which will not give the best lustrous effect to a pearl. To obviate this difficulty, I have provided means whereby after dipping the pearl body into the coating solution I am enabled to 75 support the stem member on a horizontal plane and revolving the same continuously during the drying operation, to cause the coating to flow in a circular direction about the axis of the hole through the bead and 80 lie thickest about that portion of the surface which is most exposed and which is subjected to the greatest wear.

With this end in view the following is a 85 detailed description of one form of machine 90 by which my improved method may be carried out:—

With reference to the drawings, 10 designates the frame of the machine, which may be made in any suitable form in which frame 95 I have mounted two continuous parallel tracks 11 on opposite sides thereof and on one side of the machine adjacent the edge of one of these tracks and paralleling the same I have mounted a rack 12.

100 Midway between these tracks I have mounted an endless belt 13 herein shown in the form of a sprocket chain, the same running over suitable sprocket wheels 14 at opposite ends of the machine. The sprocket 105 wheel 14 at one end is mounted on a driving shaft 15 which imparts motion to this belt through the driving pulley 16.

On these tracks I have mounted and spaced apart at intervals, a plurality of head 110 members 17 whose axes are arranged to lie in a horizontal plane. Each of these head

members is provided with a sleeve 18 having ears 19 which are connected to the sprocket 13 and within this sleeve is mounted a hollow shaft 20 squared at one end 36 and provided with oppositely-disposed recesses 21 to receive the carrier gripping springs 22. On the outside of this end of the shaft is mounted a sliding collar 23 adapted to be actuated by the sliding spindle 25 mounted in this shaft.

10 The opposite end of this shaft is recessed to receive a coiled spring 24 and this sliding spindle is slightly enlarged on its outer end 26 against which enlargement the spring 24 presses to normally hold the spindle and its collar 23 in a withdrawn position.

15 The front end of this spindle is provided with a transversely disposed pin 27 which extends through a slot 28 in the shaft and engages the collar 23 whereby a forward movement of the spindle causes the collar 23 to engage the carrier block 29 to force it from its position on the squared end of the shaft.

20 25 On this shaft 20 is mounted two rollers 30 adapted to engage and roll upon the parallel tracks 11 and a gear 31 is mounted on the rear end of this shaft to engage the rack 12 and cause the shaft with its carrier block 30 to rotate as the head is moved along by the traveling belt.

30 35 The carrier block may be constructed in any suitable way but for convenience I have made the same of wood having a multiplicity of holes 34 drilled therein which are adapted to receive the ends of the holder members 32 on which the artificial pearl beads or bodies 33 are mounted.

35 40 This block is provided with a squared central opening 35 adapted to slip onto the correspondingly squared end 36 of the shaft 25 so that the spring fingers 22 will engage, bind and hold the same in position thereon. In this way each head is caused to travel 45 continuously about the endless tracks and be simultaneously rotated by engagement of its gear 31 with the rack 12, which continues until the head comes opposite the wedge or cam shaped member 37 which engages the end 26 of the spindle and forces it inwardly to discharge or disengage the carrier block from the head to drop down and be conducted away by any suitable means (not shown). By this construction 50 55 of machine the carriers after having been loaded with the freshly coated work are readily snapped onto the end of each traveling head as it presents itself. Each successive cluster of work on its carrier is then 60 revolved by the head around the axes of the carriers and at the same time carried along through the machine and by the time it has completed the rounds of the endless track it is sufficiently dried, and as described 65 above is automatically removed from its

head to make room for another, thereby providing a continuous operation of spreading the coating solution over the surface of the bead while drying.

70 The improved method of coating pearls according to this invention consists in mounting the pearl bodies on the stems 32 by inserting the stem through the usual opening in the pearl bodies, then dipping the bodies into a suitable coating solution, 75 then positioning the stems in a substantially horizontal plane and rotating them in this plane, to cause the coating to flow, while drying, over the surface of the body most exposed and subjected to wear when the pearls are strung, thereby obtaining a better coating on said surfaces. The final 80 step of this method consists in moving the body of the pearls, while being rotated, in a linear direction to facilitate drying.

85 Having thus described one illustrative embodiment of my invention and the best mode known to me for carrying out my method, I desire it to be understood that although specific terms are employed, they 90 are used in a generic and descriptive sense and not for the purpose of limitation, the scope of the invention being defined and limited only by the terms of the appended 95 claims.

95 I claim:

1. A machine of the character described comprising a traveling head, a carrier on the head on which a plurality of pieces of work are adapted to be mounted, means for causing said head to travel in a linear direction and also impart a rotary motion to said carrier whereby the work travels with the head and is revolved around the axis of the carrier, and means for automatically discharging said carrier from said head at a predetermined point in its travel.

100 105 2. In a pearl coat-distributing and drying machine, a continuous track, an endless traveling belt, a plurality of heads moved by said belt along said track, releasable work carriers on the heads, means in said heads for rotating said carriers, whereby the work is revolved around the axes of the carriers, and means for automatically discharging the carriers from said heads adjacent the starting point.

110 115 3. In a pearl coat-distributing machine, a continuous track, an endless traveling belt, a plurality of carrier heads moved by said belt on said track, means for mounting the work upon said heads, means in said heads for rotating the work, means for releasably mounting the work upon said heads, and means including a rack and gear for positively rotating the work during the forward motion of its carrier head, means for automatically discharging the work from its head at a predetermined point in its travel.

4. In a machine of the character described, a continuous track, an endless traveling belt, a plurality of spaced apart work-carrying heads moved by said belt with 5 their axes disposed in a horizontal plane, means for mounting the work on said heads, a fixed rack, a gear on said head engaging said rack to rotate the head and work while traveling, and means for automatically dis- 10 charging the work from its head at a predetermined point in its travel.

5. A machine of the character described comprising an endless track, a plurality of spaced carrier heads mounted to move around 15 said track, each of said heads comprising a shaft mounted in bearing rollers, said rollers being in direct engagement with said track, an end of said shaft being adapted to receive a work-holder, a rack bar on the 20 frame and co-extensive with said track, a gear fast to said shaft and meshing with said rack bar, whereby the shaft is rotated as the head travels over said track, and means moving said heads over said track.

25 6. A machine of the character described comprising a frame having a pair of spaced endless tracks thereon and running parallel with each other, a shaft extending transversely across the frame and having traction 30 rollers mounted thereon which engage said tracks, a sleeve surrounding the shaft and disposed between said rollers, an endless belt connected with said sleeve for moving said shaft around said track, a work-holder re- 35 movably secured to an end of said shaft, a gear fast on the other end of the shaft, a rack on the frame co-extensive with said track and with which said gear meshes, whereby the shaft is rotated while it moves 40 around the track.

7. A machine of the character described in claim 5, further characterized by said work-holder being releasably secured on the shaft, a reciprocating bar within the shaft 45 having one end thereof normally yieldably held to project from the end thereof, the other end of the bar having means to engage and eject the workholder from the end of the shaft, and a trip device arranged to 50 engage said outwardly projecting end of the bar at a predetermined point in the travel of said heads, whereby said bar is slidably actuated within said shaft and ejects said workholder.

55 8. A machine of the character described in claim 5, further characterized by the end of the shaft adapted to receive the work-holder having resilient springs thereon lying substantially in a direction parallel with the 60 shaft, a workholder adapted to be fitted over the end of the shaft, whereby said springs frictionally grip and releasably retain it in position.

9. A machine of the character described 65 comprising a frame having a pair of spaced

and endless tracks extending in a substantially horizontal direction, a plurality of carrier heads mounted in the frame to move over said tracks, each of said heads comprising a shaft having traction rollers 70 mounted thereon engaging said tracks, a pulley at each end of said tracks, an endless belt passing over said pulleys and having said heads connected thereto in spaced relation, means for imparting motion to said 75 belt whereby the heads are moved around said tracks, one end of said shafts of said heads projecting beyond the frame exterior of the machine, workholders receivable on said projecting ends of the shafts, and 80 means for causing said shafts to rotate as the heads travel around said tracks.

10. A machine of the character described in claim 9, further characterized by a rack bar co-extensive with said track and ar- 85 ranged on the machine adjacent the other end of said shafts of the heads, and gears on said other ends of each of said shafts meshing with said rack bar, whereby the shafts are rotated as the heads move around 90 said track.

11. A machine of the character described, comprising a traveling head, a rotatable shaft on the head, a work holder releasably secured on the shaft, a reciprocating bar 95 within the shaft having one end thereof normally yieldably held to project from the end of the shaft, the other end of the bar having means to engage and release the work holder from the other end of the shaft, 100 and a trip device arranged to engage said outwardly projecting end of the bar at a predetermined point in the travel of said head, whereby said bar is slidably actuated within the shaft and releases said work 105 holder.

12. A machine of the character described, comprising a traveling head, a rotatable shaft on the head, a work holder releasably secured on the shaft, a reciprocating bar 110 within the shaft having one end thereof normally yieldably held to project from the end of the shaft, the other end of the shaft having resilient springs thereon lying substan- 115 tially in a direction parallel to the shaft, a work holder adapted to be fitted over the end of the shaft, whereby the springs frictionally grip and releasably retain the work holder in position, and means engaging the said projecting end of the shaft for causing 120 the same to move to release said work holder from said head.

13. A method of distributing a coating material over the surface of an artificial pearl, which consists in mounting the body 125 member of the pearl on a stem, rotating said stem and body on substantially a horizontal plane after a coating solution has been applied thereto to cause the coating to flow, while drying, over the surface of the body 130

frost exposed and subjected to wear, when the pearls are strung.

14. An improved method of applying a coating material to the surface of an artificial pearl, which consists in mounting the body member on a stem, in dipping the body member into the coating solution, rotating the said stem and body member to cause the

coating to flow while drying over the surface of the body and moving the body 10 through the air in a linear direction while rotating, to facilitate drying, and spreading the coating over the body.

In testimony whereof I affix my signature.

WALTER D. WOOD.
